COVERED WASTE RECEPTACLE

William B. Raftery, Winchester, Va., assignor to Rubbermaid Commercial Products, Inc., Winchester, Va.

Filed Apr. 28, 1975, Ser. No. 572,347

Term of patent 14 years

Int. Cl. D7—07

U.S. Cl. D7—194

FIG. 1

FIG. 2

FIG. 3

FIG. 4

FIG. 5

FIG. 1 is a front perspective view of a covered waste receptacle showing my new design, shown in closed position.

FIG. 2 is a similar view in open position.

FIG. 3 is a cross-sectional view on line 3—3 of FIG. 2.

FIG. 4 is a rear elevational view thereof in closed position.

FIG. 5 is a bottom plan view in closed position.

I claim:

The ornamental design for a covered waste receptacle, as shown and described.
